UNITED STATES PATENT OFFICE.

HORACE B. McCABE, OF MADISON, WISCONSIN, ASSIGNOR TO GISHOLT MACHINE COMPANY, OF MADISON, WISCONSIN, A CORPORATION OF WISCONSIN.

TIME-RECORDING REGISTER.

1,403,044.

Specification of Letters Patent. Patented Jan. 10, 1922.

Application filed October 1, 1920. Serial No. 414,072.

To all whom it may concern:

Be it known that I, HORACE B. McCABE, a citizen of the United States, residing at Madison, in the county of Dane and State 5 of Wisconsin, have invented certain new and useful Improvements in Time-Recording Registers, of which the following is a specification.

This invention relates to recording registers or stamps of that class in which the recording type changes periodically, being electrically actuated and controlled by a master clock having suitable contacts for closing and opening the circuits, and adapted to be used for recording definite periods 15 of time spent by workmen on jobs in manufacturing establishments, as a basis for determining the cost of such labor.

The improvements forming the subject- 20 matter of the present invention have been designed more particularly as improvements upon a time-recording register, successive developments of which form the subject-matter of certain patents heretofore granted 25 to me as follows: No. 946,858, dated January 18, 1910; No. 1,063,272, dated June 3, 1913; No. 1,104,125, dated July 21, 1914; No. 1,117,213, dated November 17, 1914; No. 1,129,996, dated March 2, 1915; and No. 30 1,215,683, dated February 13, 1917.

In Letters Patent No. 1,063,272, above noted, I have disclosed a mechanism for recording overtime work on cards other than those used for recording regular work, without involving any advancement of the counting mechanism between the close of regular time on one day and the beginning of regular time on the next succeeding day, such mechanism being in the nature of an idling 35 mechanism which limits the operation of the counting mechanism to the units and tens wheels, automatically returning the latter to initial positions at the conclusion of the full overtime period.

In Letters Patent No. 1,117,213, above noted, I have disclosed a mechanism for printing on the regular work cards a character or symbol indicating overtime work, that is, work usually performed at night or

on Sundays or holidays; and in association 50 with such overtime printing mechanism I have also disclosed in the said patent an idling mechanism for limiting the operation of the counting mechanism to the units and tens wheels the purpose of such mechanism 55 being to avoid any interruption in the function of the register to correctly record the periods of regular work from day to day, while at the same time providing for the recording of maximum or less periods of overtime work.

In the device of my said Patent No. 1,117,213, I have provided a polarized magnet controlled by a manually operated shift lever for throwing the overtime printing mechanism and the counter idling mechanism into and out of operation each night and morning while the shop is doing overtime work. My present invention carries this principle a step further by providing an automatic 70 clock-controlled mechanism, which may itself be rendered operative or inoperative by manually set mechanism, by which the overtime printer and the idling mechanism are automatically thrown on between the 75 close of regular working hours and the beginning of overtime working hours (for instance at 6 p. m.), and automatically thrown off ten hours later at the close of the full overtime working period (4 a. m. in the instance assumed); so that, if the factory is working overtime for a considerable period, the register can be manually set for overtime printing, and it will then automatically register both overtime work and regular 80 work on the same cards without any interference or confusion in the records, and without requiring the manual operation of a shift-lever each night and morning. I have also, in my present invention, equipped 85 the counter with a day wheel, that is, a wheel bearing numerals from one to thirty-one inclusive indicating the days of the month, and this day wheel is also actuated by the automatic mechanism above referred to.

This automatic mechanism I have herein styled an alternating mechanism for the reason that it is actuated twice every twenty-

four hours, preferably at four o'clock in the morning and at 6 o'clock in the evening, and alternately performs two different sets of functions. When actuated in the morning it performs the three-fold function of (1) throwing and locking the overtime printer out of printing position; (2) throwing the counter idling mechanism out of operation; and (3) advancing the day wheel one step; 10 and when actuated in the evening it performs the three-fold function of (1) releasing the overtime printer and permitting it to move into printing position under the impulse of a spring; (2) throwing the counter idling mechanism into operation; and (3) moving the actuating pawl of the day wheel into a position to shift the latter at the next actuation of the alternating mechanism.

20 In the accompanying drawings I have illustrated one practical embodiment of the present invention as applied to and embodied in a time register of the class disclosed in my former patents above referred to; and referring thereto;

Fig. 1 is a front elevation of the machine, with some parts omitted for the sake of clearness, and showing my present improvements embodied therein;

30 Fig. 2 is a vertical front to rear section taken substantially on the line 2—2 of Fig. 1 with some parts omitted, this view also including the box or casing in which the machine is mounted, and showing the actuating magnet of the alternating mechanism;

Fig. 3 is a vertical front to rear section taken substantially on the line 3—3 of Fig. 1, and with some parts omitted;

40 Fig. 4 is a vertical section taken substantially on the line 4—4 of Fig. 1;

Fig. 5 is a vertical section of the counters and counter idling mechanism;

Fig. 6 is a top plan view of the day-wheel actuating mechanism;

45 Fig. 7 is a detail side elevation of the overtime printing and counter idling devices and the manually operated devices for locking said parts in their inoperative positions, the figure showing such inoperative positions;

Fig. 8 is a perspective detail of the hinged yoke member that carries the overtime printing type; and

55 Fig. 9 is a diagram showing a simple form of automatic clock-controlled make and break mechanism for the circuit of the magnet that actuates the alternating mechanism.

Referring to the drawings, 10 designates 60 as an entirety a rectangular box or casing having a removable lid or cover 11. In the lower portion of the box 10 is an electromagnet 12 having an armature 13 pivoted at 14 to a bracket arm 15 and carrying a 65 forwardly extending arm 16 equipped at its

free end with a lateral pin 17. The magnet 12 is in an electric circuit that is controlled by make and break devices hereafter described on a master clock, that operate to close the circuit through the magnet 12, 70 twice in each 24 hours at the beginning and end of a full overtime working period of ten hours as, for instance, at .6 p. m. and 4 a. m. The armature lever arm 16 and pin 17 constitute the magnet-actuated means 75 for operating the alternating mechanism hereinafter described.

The register is equipped with a counting mechanism similar to that shown in my prior patents and comprising units, tens, 80 hundreds, and thousands indicating and printing wheels 18, 19, 20, and 21, respectively, Fig. 5, with actuating ratchets 22, 23, 24, 25 therefor, and a pivoted pawl 26 that is actuated at regular intervals, preferably six minutes apart, in one direction by a magnet 27 and in the opposite direction by a spring 28, through a circuit controlling mechanism on the master clock, and such as is fully shown and described in my former 85 Patent No. 1,104,125, or such as is shown, in a simpler form, in Fig. 9 hereinafter described.

In addition to the period indicating wheels and the counting mechanism I have included, in coaxial alinement with the latter, a day wheel 30 and actuating ratchet 31 and a manually set month wheel 30' (Fig. 5.)

32 designates a yoke-shaped member, one arm 32' of which is hinged on or coaxial with the shaft 29, (Fig. 2), while the other arm 32^a (Figs. 4 and 5) is likewise hinged on or coaxial with shaft 29 between the day wheel 30 and the thousands wheel 21, and has a rearwardly extending portion 33 carrying at its free end a type 34, such as the symbol X, denoting overtime work. The type symbol 34 lies in the same peripheral plane as the type characters of the several indicating wheels, and is adapted to be 100 shifted, by the rocking of the yoke 32, into and out of printing position. It is normally held in the printing position shown in Figs. 1, 3, and 4 by the tension of a pull spring 35 (Fig. 1) anchored at its lower end to the 105 yoke 32 and at its upper end to a bracket 36 mounted on one of the side frame members of the machine.

Referring next to the means for actuating the day wheel 30, 37 designates a fixed shaft 110 on which is pivoted an arm 38 carrying at its free end a weight 39, and just inwardly of the weight a laterally extending stud 40. On the other side of the arm 38 is a small shaft 41, on the end of which is pivoted a hook-pawl 43, the upper hooked end of which engages with the teeth of the ratchet 31 of the day-wheel 30, being normally urged into engagement with the ratchet by a coil spring 44 (Fig. 6) surrounding the shaft 41. 115 120 125 130

When the arm 38 is raised to the position shown in Fig. 3, it carries the pawl 43 upwardly into engagement with the next tooth of the day-wheel ratchet, and when the arm 38 drops to the position shown in Fig. 2, the pawl turns the ratchet wheel to the extent of one tooth, thus advancing the day-wheel.

Rigidly mounted on the arm 38 is an up-standing arm 45, by which the day-wheel 10 can be manually set through an opening (not shown) in the cover or lid 11.

Referring next to the counter idling mechanism, 46 designates a rigid vertical frame plate on which is pivoted at 47 an elbow lever one arm 48 of which has a laterally extending foot 49, while the other arm 50 carries a transverse pin 51 that is free to play up and down through an opening 52 in the frame-plate 46.

20 When the elbow-lever is in the position shown in Fig. 3, the foot 49 is in a position wherein it lies directly below a lateral extension 53 (Fig. 5) on the counter actuating pawl when the latter is at the rear point of 25 its swing where it drops behind the next tooth of one or more of the indicating wheel ratchets; and the position of the foot 49 is such that it will permit the pawl to drop into driving engagement with the ratchets of the 30 units and tens wheels, but will not permit it to drop low enough to engage the hundreds and thousands wheels; thereby limiting the counting mechanism to the units and tens wheels and not disturbing the position of the 35 hundreds and thousands wheels. When, however, the elbow-lever is in the position shown in Fig. 2, the foot 49 is swung out of co-operative relation to the pawl and does not affect the operation of the latter.

40 I will next describe the mechanism intervening between the armature lever 16 and its pin 17 and the driving pawl of the day-wheel, the overtime printer, and the counter idling device last described, whereby the day-wheel is advanced one step each 24 hours, and the overtime printer and idling mechanism are alternately put into and out of commission at the beginning and end of the full ten-hour overtime working period; this mechanism constituting what I have hereinbefore 45 termed an alternating mechanism by reason of the fact that it alternately performs two distinct sets of functions or operations.

Rigidly mounted within the machine is a 50 vertical frame-plate 54. On a fixed stud 55 carried by the frame-plate 54 is a pivoted arm 56, and suspended from the arm 56 on a stud 57 is a pendant 58, the lower arc-shaped end of which lies directly above the pin or 55 stud 17 of the armature lever arm 16 and is adapted to be raised by the latter.

The range of swing of the pendant 58 is limited by a fixed pin 59 on the arm 56 engaged with a hole 60 in the pendant 58; and 60 the downward swing of the arm 56 is limited

by a stop pin 61 on the plate 54. Also pivoted at 62 on the arm 56 is a triangular pawl 63 carrying at its upper end a lateral pin 64 lying within a notch 65 in the upper edge of the arm 56, and at its lower end a similar 70 lateral pin 65 which is designed simply to prevent the possibility of the pawl 63 swinging to an inverted or partly inverted position.

On a pivot stud 66 mounted in the frame-plate 54 above the arm 56 is a three-arm lever, consisting of two approximately horizontal arms 67 and 68, and a substantially vertical arm 69. The arm 67 carries a lateral pivot pin 70 extending through a vertical 80 slot 71 in the frame-plate 54, and on this pin 70 is mounted the lower end of an upright bar 72, the upper end of which bar, as best shown in Fig. 4, has a vertical slot 73 engaged with a guide stud 74, by which the 85 reciprocations of the bar 72 are maintained in a substantially vertical line. On the bar 72 are formed three lateral projections or shoulders. The lowermost shoulder 75 lies directly beneath and has a lifting engagement with the pin or stud 40 carried by the arm 38 which, it will be remembered, effects the raising of the pawl of the day counter wheel into engagement with the ratchet of the latter. The intermediate shoulder 76 lies 90 within a notch 77 (Figs. 1 and 8) formed in the upper edge of the overtime printer-yoke 32, and, on the descent of the bar 72, forces said yoke downwardly to the inclined position shown in Fig. 2, throwing the overtime printer out of printing position. The uppermost shoulder 78 overlies the lateral pin 51 (Fig. 4) carried by the elbow-lever which forms a part of the counter idling mechanism. From the foregoing it will be 105 seen that at each upward movement of the bar 72 the actuating pawl 43, of the day wheel is raised to working position on its ratchet 31, the overtime printer is allowed to move into printing position under the impulse of its spring 35, and the counter idling mechanism is likewise permitted to shift into working position under the impulse of a coil spring 79 (Fig. 5); this being the position 110 of the parts as shown in Fig. 3; while on the downward movement of the bar 72 the actuating pawl of the day-wheel is drawn downwardly by the weight 39, the overtime printer is likewise forced downwardly out of printing position, and the counter idling mechanism is thrown into inoperative position, this being the position of the parts as 115 shown in Fig. 2.

The bar 72 is raised by a weight 80 mounted on a stud 81 carried by the lever arm 68, 120 said stud extending through an opening 82 in the frame-plate 54. Since the bar 72 remains in its lowered position during the regular working hours of the day, means must be provided for locking it against ris- 130

ing under the gravity impulse of the weight 80, and for releasing it prior to the beginning of overtime work. This mechanism comprises the following parts:

5 83 designates a catch member which is pivoted to the frame-plate 54 at 84 and carries at its upper end a stud 85 projecting through an opening 86 in the frame-plate 54 and carrying a weight 87 (Fig. 4) which causes 10 the catch to normally assume the position shown in Fig. 2.

On the stud 81 is a disc 88 which lies directly above the free end of the arm 56, and when, with the parts in the relative positions 15 shown in full lines in Fig. 3, the arm 56 is raised, the three-arm lever is rocked on its pivot 66 to the dotted line position shown in Fig. 3, whereupon the catch 83 drops behind the vertical arm 69 of said lever, as 20 shown in Fig. 2, thereby locking the weight 80 in raised position and at the same time locking the bar 72 in lowered position.

On the next upward movement of the arm 56, the catch 83 is retracted to permit the 25 weight 80 to drop and the bar 72 to rise. This is effected by means of an elbow-shaped trigger pivoted at 89 on the catch 83, said trigger having a depending arm 90 formed with a shoulder 91 near its lower end, and a 30 weighted lateral arm 92, the lower edge of which rests on a stop pin 93 on the catch 83. With the parts in the positions shown in Fig. 2, when the arm 56 next rises, the pin 64 carried by the pawl 63 strikes the 35 shoulder 91 thereby raising the catch 83 out of engagement with the lever arm 69, and thus permitting the weight 80 to drop and the bar 72 to rise, assuming the positions shown by full lines in Fig. 3. When this 40 occurs, the trigger arm 90, under the influence of the weighted arm 92 swings to the left, carrying the shoulder 91 to one side of the path of movement of the pin 64. At this time the catch 83 is resting on the upper edge 45 of the lever arm 69. This primes the machine for registration of overtime work.

At the conclusion of the full overtime period of ten hours or one hundred of the six minute intervals at which the units and tens 50 printing wheels are advanced, the magnet 12 is again energized, the arm 56 thrown upwardly, and the three-arm lever is rocked to the dotted line position shown in Fig. 3 which permits the catch 83 to drop back into 55 holding engagement with the three-arm lever and returns the shoulder 91 into the path of the pin 64, said pin having passed by the shoulder on its preceding upward movement due to the fact that the shoulder was shifted 60 to the left out of the path of the pin. This primes the machine for registration of regular day work.

From the foregoing it will be seen that on the up and down movement of the arm 56 65 which occurs in the morning prior to the

commencement of regular day working time, the parts are shifted from the full line position shown in Fig. 3 to the full line position shown in Fig. 2; and with the parts as shown in full lines in Fig. 3, the bar 72 is held in 70 raised position by the gravity effect of the weight 80, supplemented by that of the disc 88.

The register, equipped with the improvements thus far described, is capable of registering on the same cards and without any confusion or interference, both regular and overtime work; but since in many factories overtime work is only an occasional occurrence, I have further equipped the machine 80 with a simple manually operable means by which the overtime register features of the machine may be permanently locked out of commission and brought back into commission when and as desired.

Describing this manually operated means, which is best shown in Fig. 7, 94 designates an elbow-shaped locking arm that is pivoted at 95 to the frame-plate 46, and carries near its upper end a lateral pin 97. The pin 97 90 lies crosswise of a locking pawl or detent 98 that is pivoted at 99 to the frame-plate 46 and has formed in its upper edge two opposed inclines or cams 100 and 101. The opposite arm of the pawl 98 is connected by a tension spring 102 to the corresponding arm of a second detent pawl 103 pivoted at 104 to the frame-plate 46 and formed on its lower edge with cam inclines 105 and 106. By pushing the pin 97 inwardly, it rocks the 100 pawl 98 and rides from the cam 100 onto the cam 101, thereby throwing the inner end of the locking arm 94 down onto the pin 51 carried by the arm 50 of the counter idling mechanism, forcing the latter out of commission. On the same pivot 95 is an elbow-lever, the vertical arm 107 of which carries a lateral pin 108 that is shiftable between the outer and inner cams 105 and 106, as shown in Fig. 7. The other arm 109 of this lever 110 strikes the top edge of the yoke 32 of the overtime printer and rocks and locks the latter out of printing position. When, therefore, the factory is not working overtime, by simply shifting the two pins 97 and 108 115 from their outer to their inner positions, the overtime features of the machine are manually thrown out of commission. The next time the factory starts on a period of overtime work, the machine is quickly primed 120 to register the latter by simply drawing the pins 97 and 108 rearwardly to their outermost positions shown in Figs. 2 and 3. It should be understood, however, that this manually operated mechanism last described 125 is not a necessary adjunct of the machine, and may be omitted; since no disturbance of, or interference with, the regular normal functioning of the machine to record regular day working periods can arise from per-

mitting the overtime printing mechanism to function idly when no overtime work is being done.

To energize the auxiliary magnet 12 any approved clock-controlled circuit make and break devices operating at the described intervals may be employed; but in Fig. 9 I have illustrated diagrammatically a simple mechanism for this purpose, in which the 10 battery and a portion of the circuit of the printing magnet 27 may be utilized in the circuit of the auxiliary magnet 12. Referring to Fig. 9 A designates the center arbor of a clock movement, fast on which is a disc 15 B carrying ten contact pins C spaced thirty-six degrees apart around its periphery. The disc B, of course, makes one revolution each hour. D indicates a battery or other source of current, from one pole of which extends a 20 line wire E connected by an insulated binding screw F to a spring contact arm G resting on the arbor A. From the other pole of the battery extends a line wire H leading into both of the magnets 12 and 27. From 25 the magnet 27 extends a line wire I connected to a spring contact arm J, the free end of which makes and breaks the circuit of the magnet 27 through the contact pins C every six minutes, thus energizing the printing 30 magnet 27.

Mounted on the frame of the clock movement is an overtime control wheel K which is geared to make one complete revolution each twenty-four hours. On the face of 35 this wheel K are two pins or studs L, L', the former spaced one hundred six minute periods, or ten hours, in advance of the latter relatively to the direction of rotation which is clockwise. Pivoted on a stud M 40 is a block N of insulating material to which is secured a spring contact arm O, the free end of which lies opposite, but normally out of contact with, the contact pins C, being drawn away from the latter by a pull spring 45 P. From the spring P extends a line wire Q to the auxiliary magnet 12, the rest of the circuit of magnet 12 being comprised by the line wire H, battery D, line wire E, contact arm G, arbor A, disc B and contact 50 pins C. Fast on the pivoted block N is a depending arm R having a cam-shaped lower end R' that is struck by pin L at say 6 p. m. to close the circuit of the auxiliary magnet 12 through the arm O and one of 55 the contact pins C, and again, ten hours later, by the pin L' to again close the same circuit. The ten hour spacing of the pins L and L' corresponds to ten complete revolutions of the units wheel and one complete 60 revolution of the tens wheel of the counting mechanism; so that when the overtime printing mechanism has been put out of commission by pin L', the units and tens wheels read exactly the same as they did 65 when the overtime printing mechanism was

put into commission by the pin L, and during this ten hour period the hundreds and thousands wheels have been kept stationary by the counter idling mechanism.

It is believed that the nature, purposes 70 and advantages of my present improvements will be readily understood from the foregoing description; and for a fuller understanding of the complete machine reference may be had to my former patents 75 hereinabove identified. To those skilled in the art it will be manifest that the particular mechanism which I have herein illustrated and described for accomplishing the purposes of the invention herein claimed 80 may be considerably modified in detail without involving any departure from the operative principles employed and without sacrificing any of the advantages secured. Hence, I reserve all such variations and 85 modifications as fairly fall within the scope and purview of the appended claims.

I claim:

1. In a time recording register, the combination with a plurality of number indicating and printing wheels, of means, including an electric circuit, a magnet in said circuit, and clock-controlled circuit make-and-break devices, for periodically advancing said wheels, a member carrying a printing type movable into and out of the printing line of said wheels, and means, including an electric circuit, a magnet in said circuit, and other clock-controlled circuit make-and-break devices, for periodically moving said member. 95

2. In a time recording register, the combination with a plurality of number indicating and printing wheels, of means, including an electric circuit, a magnet in said circuit, and clock-controlled circuit make-and-break devices, for periodically advancing said wheels, an overtime printing member carrying a printing type movable into and out of the printing line of said wheels, means, including a normally open electric circuit and a magnet in said circuit, for moving said overtime printing member, and a clock-driven wheel carrying spaced members operating to close said normally open circuit at the beginning and at the end of the full overtime working period. 110

3. In a time recording register, the combination with a plurality of number indicating and printing wheels, of clock-controlled means for periodically advancing said wheels, an overtime printing member carrying a printing type movable into and out of the printing line of said wheel, means including an electric circuit, a magnet in 120 said circuit, and a pair of spring-separated contacts, for moving said overtime printing member, and a clock-driven twenty-four hour wheel carrying spaced members operating to close said contacts at the beginning 125 130

and at the end of the full overtime working period.

4. In a time recording register, the combination with a plurality of number indicating and printing wheels, of means, including an electric circuit, a magnet in said circuit, and clock-controlled circuit make-and-break devices, for periodically advancing said wheels, an overtime printing member carrying a printing type movable into and out of the printing line of said wheels, a shiftable device for idling certain of said wheels, and means, including an electric circuit, a magnet in said circuit, and other clock-controlled circuit make-and-break devices, for periodically moving said overtime printing member and simultaneously shifting said idling device.

5. In a time recording register, the combination with a plurality of number indicating and printing wheels, of means, including an electric circuit, a magnet in said circuit, and clock-controlled circuit make-and-break devices, for periodically advancing said wheels, a pivoted overtime printing member carrying a printing type movable into and out of the printing line of said wheels, a shiftable device for idling certain of said wheels, means, including a normally open electric circuit and a magnet in said circuit, for swinging said overtime printing member and simultaneously shifting said idling device, and a clock-driven wheel carrying spaced members operating to close said normally open circuit at the beginning and at the end of the full overtime working period.

6. In a time recording register, the combination with a plurality of number indicating and printing wheels, of clock-controlled means for periodically advancing said wheels, a pivoted overtime printing member carrying a printing type movable into and out of the printing line of said wheels, a shiftable device for idling certain of said wheels, means, including an electric circuit, a magnet in said circuit, and a pair of spring-separated contacts, for swinging said overtime printing member and simultaneously shifting said idling device, and a clock-driven twenty-four hour wheel carrying spaced members operating to close said contacts at the beginning and at the end of the full overtime working period.

7. In a time recording register, the combination with a plurality of number indicating and printing wheels, and time controlled means for periodically actuating said wheels, of a member carrying a printing type movable into and out of the printing line of said wheels, a spring acting on said member in a manner to shift said type into said printing line, a magnet, and means controlled by said magnet operating, on one impulse of the latter to shift and hold said member out of printing position, and on the next impulse

of said magnet to release said member and permit it to move to printing position under the action of said spring.

8. In a time recording register, the combination with a plurality of number indicating and printing wheels, and time-controlled means for periodically actuating said wheels, of a member carrying a printing type movable into and out of the printing line of said wheels, a shiftable device for idling certain of said wheels, a spring acting on said member in a manner to shift said type into said printing line, a spring urging said idling device into operative position, a magnet, and means actuated by said magnet, operating to alternately actuate and release said member and said idling device, whereby said type is alternately shifted out of and into said printing line and said idling device is also alternately shifted out of and into operative position.

9. In a time recording register, the combination with a printing cyclometer, and time-controlled means for periodically actuating the same, of a day printing wheel on the cyclometer axis, a ratchet on said day wheel, an actuating pawl for said ratchet, a magnet, and means successively actuated by said magnet operating upon one actuation thereof to move said pawl into engagement with the next tooth of said ratchet and upon the next actuation thereof to cause said pawl through said ratchet to advance said day wheel one step.

10. In a time recording register, the combination with a plurality of number indicating and printing wheels, and time-controlled means for periodically actuating said wheels, of a day printing wheel on the same axis with said number indicating and printing wheels, a ratchet on said day wheel, an actuating pawl for said ratchet, a member pivoted on said shaft and carrying a printing type movable into and out of the printing line of said wheels, a spring acting on said member in a manner to shift said type into said printing line, a magnet, and mechanism actuated by said magnet operating upon one actuation thereof to simultaneously move said member in a direction to shift said type out of the printing line and advance said day wheel, through said pawl and ratchet, one step; and upon the next actuation thereof to simultaneously release said member and move said pawl into engagement with the next tooth of said ratchet.

11. In a time recording register, the combination with a plurality of number indicating and printing wheels, and time-controlled means for periodically actuating said wheels, of a day printing wheel on the same axis with said number indicating and printing wheels, a ratchet on said day wheel, an actuating pawl for said ratchet, a member pivoted on said shaft, said member carrying a

- printing type movable into and out of the printing line of said wheels, a shiftable device for idling certain of said wheels, a spring acting on said member in a manner to shift said type into said printing line, a spring urging said idling device into operative position, a magnet, and mechanism actuated by said magnet operating upon one actuation thereof to simultaneously move 5 said member in a direction to shift said type out of the printing line, advance said day wheel, through said pawl and ratchet, one step, and shift said idling device to inoperative position; and upon the next actuation 10 thereof to simultaneously release said member, move said pawl into engagement with the next tooth of said ratchet, and release said idling device.
12. In a time recording register, the combination of a pivoted member carrying an overtime printing type, a pivoted counter idling device, a spring tending to move said member in a direction to carry said overtime printing type into printing position, a 15 spring urging said counter idling device into operative position, a reciprocating bar operating when moved in one direction to rock said member and idling device against the force of said springs, and when moved in 20 the opposite direction to release said member and idling device, an electro-magnet, means intermediate the armature of said magnet and said bar for shifting the latter in one direction, a weight for shifting said 25 bar in the opposite direction, and a catch for holding said bar against the shifting action of said weight.
13. In a time recording register, the combination of a pivoted member carrying an overtime printing type, a spring tending to move said member in a direction to carry said overtime printing type into printing position, a reciprocating bar operating when moved in one direction to rock said member 30 against the action of said spring, and when moved in the opposite direction to release said member, an electro-magnet, means intermediate the armature of said magnet and said bar for shifting the latter in a direction to rock said member, a weight for shifting said bar in the opposite direction to release said member, a catch for holding said bar against the shifting action of said weight, and a catch releasing device alternately operated and idled by said magnet.
14. In a time recording register, the combination of a pivoted member carrying an overtime printing type, a spring urging said member in a direction to carry said overtime printing type into printing position, a pivoted lever, a bar pivoted to one arm of said lever and having a lateral shoulder adapted to strike and swing said member against the action of said spring, a weight 60 on the opposite arm of said lever, said weight tending to actuate said bar in a direction to release said member, a magnet, means intermediate the armature of said magnet and said lever for swinging the latter against the gravity force of said weight, a catch for holding said lever against the gravity force of said weight, and a catch releasing device alternately operated and idled by said magnet.
15. In a time recording register, the combination with a plurality of number indicating and printing wheels, and time-controlled means for periodically actuating said wheels, of a pivoted member carrying a printing type movable into and out of the printing line of said wheels, a spring urging said member to a position wherein said type lies in said printing line, a magnet, mechanism actuated by said magnet operating upon one actuation thereof to swing said member to, and lock it in, a position wherein said type is out of said printing line, and upon the next actuation thereof to release said member and permit it to swing in the reverse direction, and manually operated means for locking said member out of printing position.
16. In a time recording register, the combination with a plurality of number indicating and printing wheels, and time-controlled means for periodically actuating said wheels, of a pivoted member carrying a printing type movable into and out of the printing line of said wheels, a pivoted device for idling certain of said wheels, a spring urging said member to a position wherein said type lies in said printing line, a spring urging said idling device into operative position, a magnet, mechanism actuated by said magnet operating upon one actuation thereof to swing said member to, and lock it in, a position wherein said type is out of said printing line and to swing said idling device into inoperative position, and upon the next actuation thereof to release said member and idling device and permit them to swing in the reverse direction, manually operated means for locking said member out of printing position, and manually operated means for locking said idling device in inoperative position.
17. In a time recording register, the combination with a plurality of number indicating and printing wheels, of means, including an electric circuit, a magnet in said circuit, and clock-controlled circuit make-and-break devices, for periodically advancing said wheels, a shiftable device for idling certain of said wheels, and means, including an electric circuit, a magnet in said circuit, and other clock-controlled circuit make-and-break devices, for periodically shifting said idling device into and out of operative position.
18. In a time recording register, the com-

bination with a plurality of number indicating and printing wheels, of means, including an electric circuit, a magnet in said circuit, and clock-controlled circuit make-and-break devices, for periodically advancing said wheels, a shiftable device for idling certain of said wheels during an overtime working period, means, including a normally

open electric circuit, and a magnet in said circuit, for shifting said idling device into 10 and out of operative position, and a clock driven wheel carrying spaced members operating to close normally open circuit at the beginning and at the end of the full overtime working period.

HORACE B. McCABE.
